UNITED STATES PATENT OFFICE.

MILTON A. FESLER, OF VISALIA, CALIFORNIA.

FLUID-COOLING MEANS FOR GASOLENE OR OTHER ENGINES.

942,493.

Specification of Letters Patent.

Patented Dec. 7, 1909.

Application filed March 23, 1906, Serial No. 307,596. Renewed March 9, 1909. Serial No. 482,402.

To all whom it may concern:

Be it known that I, MILTON A. FESLER, a citizen of the United States, residing at Visalia, in the county of Tulare and State of California, have invented certain new and useful Improvements in Fluid-Cooling Means for Gasolene or other Engines, of which the following is a specification.

The object of the present invention is to provide means for cooling the water circulating in the water jacket of a gasolene or explosive or internal combustion engine, or for condensing the exhaust steam from a steam engine.

15 The invention can be applied equally well for both of the above purposes but for illustration it will here be shown as applied for cooling the water of circulation in the water jacket of a gasolene engine.

20 In the accompanying drawing, Figure 1 is a side elevation of the engine; Fig. 2 is a section of the fly wheel on the line 2—2 of Fig. 4; Fig. 3 is a vertical section through the relief tank; Fig. 4 is a section on the 25 line 4—4 of Fig. 1.

Referring to the drawing, 1 represents the shaft of a two-cylinder engine, such as is commonly used for automobiles, having cranks 2 driven by pistons in the cylinders 3, all of the usual construction. Upon the projecting end of said shaft is secured the fly wheel 4 in which my invention is mainly embodied. Said fly wheel comprises a hub 5 secured upon the shaft, a hollow rim 6, 35 and hollow spokes 7 extending from said hub to said rim. By means of radial partitions 8, said rim is divided into compartments 9, each connecting with two adjacent hollow spokes, so that the number of compartments is one-half the number of spokes. 40 For the purpose of illustration it may be supposed that there are eight such spokes and four such compartments.

The water of circulation passes from the 45 tops of the water jackets 10 by pipes 11 to inlets 12 in an outer tube 13, which tube discharges at its end into an annular chamber 14 formed in the hub 5 of the fly wheel. From said chamber it flows by means of 50 four passages 15 formed in said hub into four of the hollow spokes 7, thus entering the four compartments in the hollow rim. From said compartments it flows back by the other four spokes 7 to passages 16 55 formed in the hub of the fly wheel and thence to a chamber 17 formed in said hub

and connecting with an inner tube 18, which tube conducts the water into the casing 19 of a centrifugal pump. These inner and outer tubes 13, 18, are made water-tight by 60 means of stuffing boxes 20, 21. The runner 22 of the pump is secured upon a small shaft 23 extending from, and revolving with the shaft of the engine. By means of said runner the water is forced out of the casing 65 19 and flows by two pipes 24 to the lowest parts of the water jacket. In these water jackets the water is again heated and circulates in the same manner as before, the change in temperature which here takes 70 place assisting the circulation positively effected by the centrifugal pump.

In order to allow for the expansion and contraction of the water as it varies in temperature there is provided a small receptacle 75 25 connected with the water circulation and closed by a plug 26. When the water and the contained air expand owing to the rise of temperature the air can escape through a 80 small vent hole 27 in the plug.

In passing through the hollow spokes the water is exposed to a great extent of cooled surface, the spokes being comparatively wide and thin, and in order to increase the cooling effect, said spokes are arranged, oblique to the axis of the fly wheel somewhat like the blades of a rotary propeller. This form induces a strong current through the fly wheel which has a rapid cooling effect on the surfaces of the spokes and the rim of the 90 fly wheel, thus tending to rapidly cool the water circulating therethrough. The mode of application of the invention to condense the exhaust from a steam engine is obvious. It is also to be observed that, on account of 95 the centrifugal pump operating in unison with the shaft of the engine, the circulation and therefore the cooling effect increase in proportion to the speed of the engine, a very desirable result.

100 To cool the water in water jackets of gasolene engines of automobiles, or condense the steam in those which are propelled, it is customary to rely principally or entirely upon the movement of the vehicle 105 itself to provide the current of air which cools the water or steam, as the case may be. It is true that in some cases a fan is used to assist this cooling effect, but this assistance is comparatively slight, and moreover it 110 necessitates the employment of extra parts.

By the present invention the radiator

pipes at present in common use with automobiles and which are exposed to the currents of air as the vehicle is traveling are entirely dispensed with, thus saving weight 5 as well as the cost of the parts. Moreover in the present invention the water of circulation is added to the weight of the fly wheel, and in fact forms part of the fly wheel, and thus not only is the weight of the pipes 10 avoided but the weight of the water itself is utilized to form part of the fly wheel, thus saving in the amount of metal required to be used for the fly wheel. Hence manufacturers of automobiles can now dispense 15 with the water tank, and water pipes and connections, and of a considerable part of the fly wheel.

A further important advantage of the 20 present invention is that the water, being much more effectively cooled than with prior devices for this purpose, cannot reach the boiling point, and there is much less escape of water by evaporation. With prior devices, in hot climates, or where the roads 25 are hot and dusty, or where the engine is running while the vehicle itself is standing still and consequently there is not sufficient circulation, it frequently happens that the 30 water of circulation reaches the boiling point and consequently passes off as vapor and has to be renewed. With the present invention this cannot take place, and consequently there is not the necessity of furnishing 35 a large water tank for holding a sufficient supply of water to provide for this evaporation.

It will of course be understood that with the present invention the water can be kept 40 cold while the car is standing still, just as well as when it is moving, because the motor can be started to run at any speed which effects a rapid circulation.

One of the greatest annoyances in automobileing is the carbonization of the lubricating 45 oil which wears out the piston and cylinder and this carbonization is caused to great extent by over-heating. By means of the present invention, in which the cooling is more effectively accomplished, this over-heating 50 and consequent carbonization are avoided.

I claim:—

1. In combination with an engine of the class in which a fluid is cooled for re-use, a hollow fly wheel driven by the engine, having hollow spokes connected with the rim of the fly wheel said spokes being elongated in

cross section and the general direction of said cross section being oblique to the axis of the fly wheel, and means for conducting the fluid to and from said spokes, substantially 60 as described.

2. In combination with an engine of the class in which a fluid is cooled for reuse, means for so cooling the fluid comprising a fly wheel driven by the engine and having a 65 hollow rim, hollow spokes leading thereto, a hub having passages individually connected with said spokes, and means for conducting the fluid to one passage and from another passage, substantially as described. 70

3. In combination with an engine of the class in which a fluid is cooled for reuse, means for so cooling the fluid comprising a fly wheel driven by the engine and having a 75 hollow rim, hollow spokes leading thereto, a hub having passages individually connected with said spokes, means for conducting the fluid to one passage and from another passage, and a rotary pump revolving in unison with the fly wheel, and imparting movement 80 to the fluid, substantially as described.

4. In combination with an engine of the class in which a fluid is cooled for reuse, means for so cooling the fluid comprising a 85 fly wheel driven by the engine and having a hollow rim, hollow spokes leading thereto, the rim of the fly wheel being divided into compartments and the spokes communicating in pairs with the compartments, a hub having passages individually connected with 90 said spokes, and means for conducting the fluid to one passage and from another passage, substantially as described.

5. The combination with an engine of the class in which a fluid is cooled for reuse, 95 means for so cooling the fluid comprising a fly wheel driven by the engine and having a hollow rim, hollow spokes leading thereto, a hub having passages individually connected with said spokes, means for conducting the 100 fluid to one passage and from another passage, inner and outer tubes, stuffing boxes therefor and connections between said tubes and the passages, substantially as described.

In witness whereof I have hereunto set 105 my hand in the presence of two subscribing witnesses.

MILTON A. FESLER.
